UNITED STATES PATENT OFFICE.

JAMES SOUTH DAY, OF NEW ORLEANS, LOUISIANA.

RECOIL-PAD FOR GUN-STOCKS.

1,123,180.

Specification of Letters Patent. Patented Dec. 29, 1914.

Application filed March 18, 1914. Serial No. 825,665.

To all whom it may concern:

Be it known that I, JAMES SOUTH DAY, a citizen of the United States, residing at New Orleans, in the parish of Orleans and State of Louisiana, have invented certain new and useful Improvements in Recoil-Pads for Gun-Stocks, of which the following is a specification, reference being had to the accompanying drawings.

This invention relates to an improved recoil pad for fire arms and has for its primary object to provide a device of this character adapted to be secured to the end of a gunstock for engagement with the shoulder of the marksman, whereby shock or jar and resultant injury to the shoulder is effectually obviated.

In its more specific aspect, the present invention embodies in its construction, a base of hard rubber or similar material adapted to be rigidly secured to the end of a gun stock, and a relatively soft rubber cushion vulcanized or otherwise secured upon said base, and provided with air chambers or pockets, whereby said cushion is rendered highly resilient.

The invention has for a still further object to provide a pneumatic recoil pad which may be easily and quickly applied to the gun stock, irrespective of its form or construction and without necessitating the employment of skilled labor.

With the above and other objects in view as will become apparent as the description proceeds, the invention consists in certain combinations, constructions and arrangements of parts as I shall hereinafter fully describe and claim.

For a full understanding of the invention, reference is to be had to the following description and accompanying drawing, in which—

Figure 1 is a section through the end of a gun stock having my improved recoil pad applied thereto; Fig. 2 is a section taken on the line 2—2 of Fig. 1; Fig. 3 is a section similar to Fig. 1, illustrating a slightly modified construction; Fig. 4 is a similar view showing a still further modification.

Referring in detail to the drawing and more particularly to Figs. 1 and 2 thereof, 5 designates the butt end of a gun stock. My improved recoil pad embodies in its construction a hard rubber base plate 6 and a relatively thick comparatively soft rubber cushioning pad 7. This pad is preferably

formed from sponge rubber and has one face longitudinally curved to substantially conform to the curvature of the marksman's shoulder upon which it is adapted to rest. 30 In the preferred embodiment of the invention, I preferably construct this cushioning member 7 hollow to provide an air chamber 8. One of the end walls of this member is provided with a valve 9 through the medium of which said member may be inflated by means of a suitable air pump. In addition to the air chamber 8 which provides an internal cushioning means when the same is supplied with air, I also form in the base wall of the member 7 which is vulcanized upon the rubber plate 6, a plurality of transversely extending air pockets 10. These pockets have free and open communication at their opposite ends with the atmosphere, 35 and while the same add to some extent to the resiliency of the member 7, it will be understood that these latter external air pockets may be dispensed with if desired, in the use of the pneumatic cushion. The hard rubber base plate 6 is provided adjacent its opposite ends with openings with which similar openings in the base wall of the cushioning member 7 are adapted to coincide. These openings receive the fastening screws 11 which are threaded into the wood stock 5. Between the heads of the screws and the wall of the soft rubber cushioning member 7, washer plates 12 are preferably arranged. The opposed walls of the cushioning member 13 are connected by the integral tubes 13, said tubes surrounding screw receiving openings formed in the base wall of said member. The outer ends of these tubes are open and are adapted to receive the shank of a screw driver which is engaged with the heads of the screws 11 to properly secure the pad to the gun stock. After the pad has thus been secured in place, the tubes 13 are closed by suitable rubber plugs indicated 14.

In Fig. 3 of the drawings, I have shown the cushioning member 7' of solid construction, said member however, being also formed of sponge rubber which is vulcanized upon the comparatively hard base 6'. The cushioning member 7' is formed with a plurality of spaced transversely extending openings 15, which are provided for a similar purpose to the air pockets 10 above referred to and greatly add to the resiliency of said cushioning member. It will be

obvious that if desired, the transversely extending air passages 10 above referred to may also be provided in the bottom face of a solid soft rubber cushion. The recoil pad shown in Fig. 3 is secured to the gun stock in the same manner as the preferred form of the invention, the ends of the soft rubber cushion member 7' being provided with openings 13' extending entirely through the same and adapted to be closed by the rubber plugs 14', after the device has been properly secured to the end of the gun stock.

In Fig. 4 of the drawings, I have illustrated still another modification, wherein the hard rubber base plate 6^a is provided in its outer face with a plurality of spaced transverse rectangular channels or grooves 16. Upon this base and extending over said grooves the soft rubber cushioning member 7^a is arranged and vulcanized to said base. The pad is secured upon the end of the gun stock as above explained and it will be apparent that by the provision of the transversely extending grooves or channels 16 in the hard rubber base, the soft cushioning member 7^a will enter said grooves and expel the air therefrom upon the recoil of the gun, thus absorbing the shock or jar which would otherwise be imparted to the shoulder of the marksman.

Any one of the several forms of the invention above described will satisfactorily accomplish the ends in view. The primary feature of course resides in the provision of the air pockets in the use of a solid rubber pad or the provision of the inflatable pneumatic pad.

My improved recoil pad may be very easily and quickly applied to the end of the gun stock and effectually operates to protect the shoulder of the gunner against all liability of abrasion or injury incident to the recoil of the gun. The device is extremely simple in its construction.

While I have above described and illustrated in the accompanying drawings the several preferred embodiments of my invention, it is to be understood that the device is susceptible of still further modifications and I therefore reserve the privilege of resorting to all such legitimate changes as may be fairly embodied within the spirit and scope of the invention as claimed.

Having thus described the invention, what is claimed is:

1. A recoil pad for gun stocks comprising a hard rubber base plate adapted for engagement with the gun stock, and a relatively soft rubber pad secured upon said base and provided with a plurality of transversely extending air pockets open at both ends to the atmosphere.

2. A recoil pad for gun stocks including a hard rubber base plate provided at its ends with screw receiving openings, a relatively soft hollow rubber cushion provided with tubular connections between its opposite walls adjacent to each end thereof, the bores of which open upon one face of the cushion, the wall of the cushion at the other ends of said tubes being provided with screw receiving openings adapted to register with the openings in said base plate, fastening screws adapted to be inserted through said bores and through said openings and threaded into the gun stock, and rubber plugs disposed in the bores of said tubes to close the same, the wall of the pad which is opposed to the base plate being provided between the tubes with a plurality of transversely extending air pockets, said pockets being open at their opposite ends to the atmosphere.

In testimony whereof I hereunto affix my signature in the presence of two witnesses.

JAMES SOUTH DAY.
